UNITED STATES PATENT OFFICE.

NYE A. BUSH, OF CHICAGO, ILLINOIS.

CANCELING-STAMP.

SPECIFICATION forming part of Letters Patent No. 367,269, dated July 26, 1887.

Application filed September 15, 1886. Serial No. 213,600. (No model.)

To all whom it may concern:

Be it known that I, NYE A. BUSH, a citizen of the United States, residing at Chicago, in the county of Cook and State of Illinois, have 5 invented certain new and useful Improvements in Canceling-Stamp; and I do hereby declare the following to be a full, clear, and exact description of the invention, such as will enable others skilled in the art to which it appertains 10 to make and use the same.

My invention relates to canceling-stamps which, by means of a rotating central disk, deface the postage-stamp by scarifying and displacing a portion of its surface; and it consists of novel constructions and arrangements of parts which will be hereinafter fully described, and pointed out in the claims, whereby this class of canceling-stamps is rendered cheap in construction, solid and compact and 15 durable, as well as positive and effective in their action upon the postage-stamp, while convenience for resharpening and repairing is afforded.

In the accompanying drawings, Figure 1 is 20 a view of a hand canceling-stamp, the cross-bar of the handle being partly in elevation and provided with an ordinary printing-head, which, with the handle, is shown in elevation and with one of my canceling-heads, which 25 latter, with one end portion of the cross-bar of the handle, is shown in section and as it appears previous to being put into operation. Fig. 2 is a central vertical section of a portion 30 of the cross-bar and the canceling-head as it appears when it has been put in operation. Fig. 3 is an elevation of the rotating tubular screw to which the canceling-head is fastened. Fig. 4 is a bottom or face view of the canceling and envelope-holding devices of the 35 canceling-head.

The letter A in the drawings represents an ordinary solid handle; B, a cross-bar fastened to it; C, an ordinary post-office printing-head fastened to one end portion of the said cross-bar; and D, my improved canceling-head 40 fastened to the other end portion of the cross-bar by means of a screw, e, which is passed through the cross-bar C and screwed into the head portion of a cap, d, and thus holds the 45 canceler to the cross-bar. The cap d is provided with a cylindrical steel or iron rim, d', with inner and outer screw-threads, as shown.

By the inner screw-thread of the rim d' a brass or alloy metal nut, E, is fastened to the cap d, having screw-threads e, of quick pitch or very great inclination, into which a tubular screw, F, having screw-threads f corresponding to the threads e, is fitted. The threads e and f are made right-handed for reasons hereinafter explained.

Into the lower end portion of the tubular screw F a disk-cutter, G, is screwed, having a stem or shank, g', with a left-hand screw-thread, g, said stem fitting a corresponding inner left-hand screw-thread, f', in the tubular screw. A horizontal annular space, g'', is left between the lower end surface of the tubular screw F and upper surface of the disk-cutter G, which space is occupied by a horizontal circular flange, h, of a sliding sleeve, H, while the disk-cutter G itself is let into a horizontal annular depression, h', formed in the sleeve just beneath the flange h. The sleeve H thus connected to the canceling-head will move with the screw F and follow it in its up-and-down movements, while it is prevented from revolving with it by means of a pin, I, which is for one half its diameter let into a groove, i, in the outer cylindrical surface of the nut E, while its other half is fitted into a gutter, 80 i', of corresponding shape in the inner surface of the sliding sleeve H. The gutter i' permits the sleeve H to slide up and down along the nut E.

The pin I is provided with a slotted head, 85 i', and screw-thread i'', by means of which it is screwed into the rim d' of cap d and groove of nut E, and when it is thus screwed into position it is embedded for half its diameter in the rim of the cap and the outer surface of the 90 nut, and it at the same time extends loosely in the gutter i' of the sleeve, and thus the pin serves the purpose of permanently holding the nut E and cap d together by preventing the turning or unscrewing of one on the other, and 95 also as a straight or vertical guide to the sleeve H.

To the outer screw-thread of the rim d' of the cap d is screwed a cylindrical housing, J, the lower end portion of which is open and 100 contracted, so as to form a stop or step, j, which serves as a lower abutment to an annular flange, h'', around the top portion of the sleeve H, while its lower or main body portion

is projecting through the lower opening of the housing, as shown in Fig. 1. In its normal position the sleeve H is forced outwardly by a spiral spring, K, inclosed in the tubular screw F, which spring bears against the cap d and disk-cutter G, thereby keeping the flange h² in contact with the step j, as illustrated in Fig. 1. The upper portion of the spring K is kept in a central position by the lower end portion of the screw e, which projects downwardly through the cap d into the spring to any extent desired. The diameter of said spring K is such that when it is fully compressed, by pushing the sleeve H into the housing J, it bears against the inner surface of the tubular screw F without bulging too much, and thus it is prevented from bulging sidewise injuriously or catching against the tubular screw or hooking into its upper corner.

The nut E is preferably made of brass, as this metal can be cut more easily than steel or iron, while the other parts, including the tubular screw F, are of steel. The screw surfaces 25 being the one of brass and the other of steel, a very smooth operation is secured.

The peculiar construction of the screw-thread for the nut E and screw F, as shown in the drawings, is the result of close observation, and is strictly in keeping with the relative hardness of each metal, the softer metal, brass, being provided with screw-threads having rounded inner corners, and thus preventing the usually rapid wear of such, and the 30 steel threads being comparatively thin, because the wear of that metal is comparatively slow.

By making the nut separate from the cap and screwing the cap upon the nut, facilities 40 for making the nut of brass are afforded, and by making the screw tubular and open at top and bottom the spring can be applied within it below cross-bar and cap, while the disk-cutter can be screwed into its lower end, 45 and thus a very solid and compact implement is produced, and the same can be taken apart for repair or other purposes very conveniently.

The lower annular face, h³, of the sleeve H is provided with eccentric-curved ridges h⁴, 50 which ridges are set opposed to the motion of the disk-cutter, and which, when the canceling stamp is pressed upon the stamp and envelope take hold thereof and prevent them from turning. The lower face, g³, of the 55 disk-cutter G is provided with rhombic or square pyramids, g⁴, with sharpened edges, which, when pressed upon the postage stamp, will enter the same, and when revolved will scarify or cut into its surface and scrape a 60 portion of it away.

The movements of the disk-cutter head upward and around are caused by simply pressing the hand canceling stamp down upon the paper with sufficient force to move the housing J over the sleeve H until its upper end surface comes in contact with the under surface of the rim d' of the cap d. During this

operation the sleeve H holds the disk-cutter G of the tubular screw F down upon the paper, and the descending nut E causes the said screw to revolve in a left-hand direction and rotate the disk-cutter G, and thereby scarify or cut and scrape off portions of the surface of the stamp, as well as mutilate the stamp more or less, according to the depth of projection of the cutters g⁴ over that of the roughened lower annular surface, h³, of the sleeve H, which surface takes a firm hold of the corners of the postage-stamp and of the paper of the envelope, holds them down flat and level, 70 and prevents them from being turned or twisted while the center of the postage-stamp is scraped or canceled.

The pyramidal points g⁴ require to be sharpened from time to time, and to provide for 75 this the disk-cutter G is adjusted vertically and in relation to the surface h³ of the sleeve H by means of thin washers placed between it and the upper surface of the depression h', one of such washers, g⁵, being shown in the 80 drawings.

It will be seen that while the canceling implement is pressed down the spring K forces the cutters g⁴ of the disk-cutter G into the postage-stamp, thereby creating a resistance 95 to the revolution of the same great enough to unscrew the cutter-head from the screw F, if their screw-threads were right-handed, or the same as the screw F; but by using the left-handed screw, as described, the cutter-head is 100 prevented from becoming loose while canceling a stamp. When the canceling-stamp is removed from the envelope, the spring K forces the tubular screw, disk-cutter G, and sleeve H down, revolving the cutter-head to the right 105 without any tendency to unscrewing the same, as the cutter-head revolves now without resistance.

I am aware that stamp-cancelers have been constructed with rotary cutters, and that such 110 cutters have been operated by a screw and nut contrivance, as shown in Letters Patent No. 229,282. I also am aware that the nut has been kept from revolving while being reciprocated by means of guide-rods, as shown in said patent. 115 My invention differs from said patent in the screw being made hollow, the spring being entirely inclosed within the screw, and all arranged below the cross-bar of the stamp-canceler.

I also am aware that a rotary cutter attached to a canceling-stamp and operated by a spiral slot and pin and having a spring above its barrel and all applied below the cross-bar or socket-plate of the handle has been devised; 125 but this construction differs widely from my construction and mode of operation, and is not as firm and positive in its action as the work required to be done requires or demands.

I also am aware of Letters Patents No. 130 233,210, 195,552, 161,528, and the Letters Patent of Barlow and Taylor, No. 225,043; but these patents show constructions different from those claimed by me; and my invention may

be regarded as an improvement thereon, it uniting in an improved organization or combination features which are common to these patented contrivances, and other features which 5 are novel in the relations shown, and in such relation produce improved results.

What I claim as my invention is—

1. The within-described hand canceling-stamp comprising in its construction a handle, 10 A, cross-bar B, flanged and internally and externally screw-threaded cap d, stepped and grooved housing J, screwed to the outside of the flange of the cap, guttered nut E, screwed into the said flange, tubular screw F, having 15 solid thread and applied entirely below the cap and cross-bar, cutter-disk G, having its shank screwed into the screw F, spring K, bearing on the said shank g and located below the said cap and cross-bar and entirely in- 20 closed by the screw F, the fastening and guiding screw e, the grooved sliding sleeve H, having the flanges h h², depression h', and roughened surface h⁴, and the pin I, screw-threaded along a portion of its surface and passed

through the cap and between the nut and housing, all substantially as and for the purpose described. 25

2. The sliding sleeve H, having a lower annular roughened face, as h³ h⁴, and formed with a flange, h, in combination with the screw F, 30 having the disk-cutter G, nut E, spring K, and washer g⁵, substantially as and for the purpose described.

3. The combination, with the sliding sleeve H, housing J, hollow screw F, having projecting thread-nut E, cap d, and the disk-cutter G, of the spring K, applied within the screw F between the cap d and disk-cutter G, and below the cross-bar or base-piece of the handle of the canceler, substantially as and for the 40 purpose described.

In testimony whereof I affix my signature in presence of two witnesses.

NYE A. BUSH.
